MACHINE FOR SIZING TILES.

1,210,557.

Specification of Letters Patent.

Patented Jan. 2, 1917.

Application filed January 5, 1905. Serial No. 239,816.

To all whom it may concern:

Be it known that I, GEORGE A. STANBERY, a citizen of the United States, residing at Zanesville, in the county of Muskingum and State of Ohio, have invented certain new and useful Improvements in Machines for Sizing Tiles, of which the following is a specification.

My invention relates to machines for ascertaining the sizes of tiles, in order that they may be assorted accurately and quickly according to their sizes.

In the manufacture of tiles of any size, say of six inches in length, it is found that they vary in length after leaving the kiln, some of them being a fraction of an inch shorter, while others are larger in fractions of an inch, than the standard gage. It is customary to assort tiles which vary a thirty-second of an inch, more or less from, the standard gage into different groups or piles; and said tiles are distinguished in the trade by appropriate characters or designations, according to their variations from the standard gage.

The machine of the present invention may be operated easily and quickly for the purpose of accurately ascertaining the grade according to size, or the length, of the tiles, and to enable the attendant to assort all the tiles of the different graduations of sizes of tiles into separate groups or piles.

My machine, also, makes provision for the measurement of tiles of different lengths, say from one or more inches up to eight, ten or more inches, each of the standard lengths of tiles, and the graduated tiles of such standard lengths, being measured and assorted accurately according to the classes thereof.

The machine is constructed to compensate for wear in its several working parts, thus insuring accuracy in the performance of its work.

Further objects and advantages of the invention will appear in the course of the subjoined description, and the actual scope of the invention will be defined by the annexed claims.

Reference is to be had to the accompanying drawings, forming a part of this specification, wherein like characters of reference are used to indicate corresponding parts in all the figures.

Figure 1 is a perspective view of a ma-

chine for sizing tiles, constructed in accordance with my invention. Fig. 2 is a view in side elevation, illustrating the employment of means for accurately positioning an adjustable but normally stationary member, the latter being adapted to coöperate with a movable member in determining the length of a tile. Fig. 3 is a plan view, omitting the casing or housing and showing several working parts of the machine. Fig. 4 is a detail view in end elevation, partly broken away and in section, showing the application of the adjusting device to the bed plate. Fig. 5 is a view partly in section, and partly in side elevation, looking toward the indicator device and the movable member, that is adapted to coöperate with the relatively fixed member. Fig. 6 is a longitudinal sectional elevation taken in the plane indicated by the dotted line 6—6 of Fig. 3, and Fig. 7 is a vertical transverse section on the line 7—7 of Fig. 3.

The base A of the machine is shown by the drawings as being substantially L-shaped, but it will be understood that the shape is immaterial and may be modified or changed at pleasure. One arm of the base is provided with a longitudinal guideway a, which may be either dovetailed or T-shaped in cross section, as shown by Fig. 4, and on the opposite sides of this guideway are provided the wear plates b, the latter being fastened removably to the base by any suitable means, such for example as the screws b'.

My machine includes in its construction two coöoperating members B, C, between which the tile is adapted to be placed in the operation of gaging the same, the member B being a relatively stationary part, although it is capable of adjustment on the base, while the member C is a movable part which is shifted at will away from the member B.

As herein shown, the member B is in the form of a head having a dovetailed or T-shaped shank, arranged to fit snugly in the guideway a. This member or head B is slideable in the guideway and over the wear plates b, said head being secured or fastened in position by any suitable clamping device, such as the bolt b². I prefer to provide a wear plate b³ on the operating or working end of the head B, said wear plate being secured removably to the head by suit-

able screws b^4 . It is evident that the screws may be removed and the wear plate b^3 reversed in position on the head, or this wear plate may be replaced by another plate when it is worn. In a like manner the plates b may be removed from the base A and reversed in position thereon, or said plates may be thrown aside and others substituted therefor, thus making provision for taking up the wear in some of the parts of the machine.

The movable member C is represented in the form of a plunger adapted normally for slidable movement toward and from the member B. Said plunger C is shown as of cylindrical form, but it will be understood that a square or polygonal plunger may be used, hence I do not desire to confine myself to said cylindrical form of plunger. Said member C is supported in a boxing or housing D, which is secured in a suitable way to the bed A. The boxing is provided with a longitudinal chamber in which the plunger C is snugly fitted, and said boxing is provided in one side with a notch or recess d , the purpose of which will presently appear. The plunger is provided at its respective ends with collars c , c' , adapted to limit the endwise movement of the plunger in the boxing, and at its working end said plunger has a gage pin c^2 , which is clamped removably to the plunger by a set screw c^3 . The plunger is drawn or impelled normally in one direction by a spring E, Fig. 5, which is arranged within a chamber e , in the under side of the bed A, one end of said spring being anchored in place in a suitable way. The other end of the spring is attached to an arm e' , which is made in one piece with the collar c' , thus connecting the spring with the rear end of the plunger, said arm e' being arranged to work in a slot e^2 , which is provided in the bed A, see Fig. 3.

The plunger is adapted to be drawn back or retracted at will by the employment of a suitable operating device, which is herein shown as a lever F, the latter being arranged in the chamber e , and projecting at its respective ends through slots in the chambered part of the bed plate, one of said slots being indicated at f , in Figs. 1 and 2. One end of the lever is fulcrumed on a short post that depends from a bracket plate f' , secured to a side portion of the bed, while the free end of the lever extends beyond that side of the machine on which the operator is stationed, thus placing the lever within convenient reach of the operator. The arm e' of the plunger is arranged in the path of the lever F when it is moved in one direction, but this lever may be moved freely in an opposite direction without engaging with said arm e' , whereby the lever when moved to the right will withdraw the plunger C away from the member B, but the move-

ment of the lever F toward the left will not affect said plunger, thus permitting the spring E to act on said plunger in moving it toward the head B. It will be understood, therefore, that the spring E and the lever F operate independently on the plunger to control the same, the spring E moving the plunger in one direction, while the lever F operates to move the plunger in an opposite direction. This construction and arrangement of parts not only provides for holding the plunger normally in position and for the convenient withdrawal of the plunger whenever desired, but it prevents an attendant from pressing on the plunger so as to force it up into engagement with a tile, it being understood that the lever cannot so act on the plunger as to move it toward the work placed between the head B and the pin c^2 of the plunger.

The plunger C is provided with a plurality of teeth g , which form a rack, the latter being exposed through the open side, d , of the boxing D. When a plunger of cylindrical form is used, the teeth g are circular and extend entirely around the plunger or rack C, but it is evident that a polygonal sided plunger may be used, in which case the rack teeth may be formed on one face of the plunger. I prefer, however, to employ the cylindrical plunger having the circular rack teeth, because the plunger can be turned axially by hand, to present other surfaces of the rack teeth in position for engagement by a toothed segment H, thus enabling the parts to be adjusted in a way to compensate for wear.

It should be understood that, in the use of the machine, the plunger or rack C has a sliding movement normally in the boxing or housing; such sliding movement being imparted thereto in one direction by the spring E, and the lever F being used to move the plunger at will in the other direction. Under this mode of using the machine, the indicator mechanism, except the pointer and the dial, are concealed by a casing, L, but this casing may be removed from the bed A, so that an attendant can gain access to the plunger C, for the purpose of adjusting it, as by turning it axially by hand, to bring fresh surfaces of the rack teeth g into engagement with the toothed segment H.

The segment H is mounted loosely on a fixed post I, and around this post is coiled a torsion spring, I', one end of which is anchored on the post, while the other end of said spring is connected with the segment, for the purpose of normally turning it toward the right or holding one tooth of the segment normally in engagement with one face of a tooth g on the rack. This construction and arrangement takes up the slack between the teeth of the segment and

the rack, thus compensating for lost motion, and insuring accuracy in the working of the several parts.

The segment H is provided with a pointer 5 J, which is adapted to traverse a dial K. Said dial is provided with a series of division lines k, one of which is inscribed with the character S, denoting the point of adjustment for the standard gage of the tile. 10 The spaces formed by the other indicating lines k of the dial are inscribed with suitable characters designating the sizes of the tiles, as for example, the spaces on the left of the standard gage line S, have the characters "A, L, XL," while the spaces on the right of said gage line are inscribed with the characters "B, C, D, S and XS." The first mentioned group of three spaces indicate the tiles that are larger in specified degrees or graduations, than the standard size, while the last mentioned group of five spaces indicate specified graduations of under sized tiles. The dial herein shown is graduated to indicate variations of a thirty 25 second of an inch in tiles, the lengths of which may slightly exceed, or be less than, the true size; yet the particular graduation of the dial, and the scale of measurement secured by said dial and the machine as an 30 entirety may be modified and changed within wide limits. It should be understood, therefore, that the dial may be marked to indicate as many or as few graduations of any and all sizes of tiles which it is desirable to measure; that the characters or 35 designations employed on the dial may be changed at pleasure, and that the dial may be graduated to measure variations in sixteenths of an inch, or sixty-fourths of an 40 inch, or in fact any fractional part of standard measurement. The dial is shown as secured to the bed A, but it is evident that a dial graduated according to one scale may be replaced by other dials graduated to 45 different scales.

The several working parts comprising the indicator mechanism, and certain parts of the plunger are inclosed within a casing L, the same being secured removably on the 50 bed plate, said casing having an observation slot m, through which the dial K is exposed.

For the purpose of accurately adjusting the head or member B, I have provided an 55 auxiliary adjusting contrivance which is adapted to be fitted removably to the bed A, in a position to coöperate with the head B. This device is shown by Figs. 2 and 4 of the drawings, and it consists of a post N, 60 having a foot piece, arranged to work in the guide-way of the base. On the post is fitted a slideable member N', and said post has a threaded stem n, on which is screwed a clamping nut n', the latter being adapted 65 to press the member N', upon the bed for

the purpose of clamping the adjusting devices detachably in place. The post N carries an adjusting screw O, which is adapted to engage with the head B, for the purpose of giving a minute accurate adjustment to 70 the latter.

The operation of my invention may be described as follows: A gage Z of the standard size of any tile is employed preliminarily for adjusting the coöperating members B, C, accurately to their working positions. The head B is moved on the bed to its approximate position, and the gage Z is placed on the bed between said head and the pin c² of the member C, see Fig. 1. 75 The auxiliary adjusting device is now placed in position and tightened by the nut n', after which the screw O is adjusted for the purpose of moving the head B, the gage Z, the plunger C, and the pointer, until 80 the latter moves to B on the dial in order to secure an exact working position of the parts. After this operation, the head B is clamped tightly in place by the screw b², the auxiliary adjusting device is detached, 85 and the gage block Z is removed, thus placing the machine in condition for use. The operator may now move the lever F to the right, so as to withdraw the plunger and increase the space between the pin c² and 90 the head B. A tile may now be dropped in place on the bed between said head and the pin, and by releasing the lever the spring E moves the plunger until the pin c² engages with the tile, whereby the adjustment 95 of the plunger gages the pointer so as to indicate on the dial the size of the tile. The lever is now operated and the tile removed and placed in a group or pile of the determined size. These operations are 100 repeated with each tile and the different sizes of tiles may be quickly and rapidly assorted. To change the gage of the machine for use on tiles of another size, the screw b² is released, and the head B adjusted length- 105 wise on the base A, the auxiliary adjusting device and the gage block Z of the required size being employed to accurately determine the position of the head B. It is evident that tiles of any size within the 110 capacity of the machine may be quickly and accurately gaged by proper adjustment of the member B with relation to the member C, and tiles of any length may be assorted according to their grade by the use of the 115 machine in the manner heretofore described.

From the foregoing description it will be seen that I have produced a simple, efficient and accurate machine which may be used in 120 ascertaining the variations or graduations in length of tiles belonging to a given size; and that the machine, by the simple adjustment of the head or member B, can be adapted for use in connection with any 125 130

other different size of tile to ascertain the variations or graduations of tiles forming sub-divisions of the main group or class.

Although I have shown and described my machine as being especially adapted for the measurement and graduation of tiles, it should be understood that the machine can be used to advantage in the work of measuring other articles and grading them according to their sizes.

Changes in the form, size, proportion, and minor details in construction may be made without departing from the spirit of the invention or sacrificing any of the advantages thereof, and I, therefore, reserve the right to make such alterations and modifications as fairly fall within the scope of my invention as defined by the annexed claims.

Having thus described my invention, what I claim and desire to secure by Letters Patent is:—

1. In a machine for assorting tiles according to their sizes, the combination of a base having a surface upon which tiles are adapted to be placed, a tile-engaging member upon the base, said member having an edge for engagement with one edge of a tile, and said edge of the member being substantially perpendicular to the tile-engaging surface of the base, a plunger having a tile-engaging face positioned in opposing relation to said edge of the tile-engaging member, said plunger being slidable relative to the tile-engaging surfaces of the base and said member, means for retaining the plunger normally in a predetermined position relative to the edge of said member, and indicating means including a pointer and a gear segment, said plunger having circular teeth meshing with said gear segment and said plunger being rotatable for changing the points of contact between its circular teeth and the teeth of said gear segment.

2. In a tile measuring machine, a bed having a guide-channel, a head fitted to said channel, means for clamping the head laterally to the bed, a post fitted in the channel and clamped to the bed, an adjusting screw carried by the post and adapted for engagement with the head, a freely-movable member slidable on the base and movable endwise with respect to the head, and indicating means actuated by said slidable member.

3. In a tile measuring machine, a bed having a guide channel, wear plates attached to said bed parallel to said channel, a jaw fitted to the channel and engaging with the wear plates, a headed stem working in the channel and having means for clamping the jaw to the bed and said wear plates, a member co-operating with the jaw, and an indicator mechanism controllable by said member.

4. In a machine for assorting tiles according to their sizes, the combination of a bed

having a plane surface upon which the tiles to be measured are adapted to be positioned, a tile-engaging member fixed on the bed and provided with a tile-gaging straight edge positioned perpendicularly to said tile-engaging surface, a slideable and rotatable plunger provided with gear teeth, said plunger having a tile-engaging face in opposing relation to said edge of the member, a spring co-operating with the plunger for retaining it normally in a predetermined position relative to said edge of said member, means operable at will for moving the plunger relative to said edge of the member, a pivoted gear segment meshing with the gear of the plunger, a spring acting on said gear segment for retaining one tooth thereof in mesh with a gear tooth of the plunger, and a pointer carried by the gear segment.

5. In a machine for assorting tiles according to their sizes, the combination of a bed having a plane tile-engaging surface, a tile-engaging member thereon, said member having a straight edge positioned perpendicularly to the tile-engaging surface, a slideable and rotatable plunger, one end of which is in opposing relation to the edge of the tile-engaging member, means for moving the plunger normally in one direction, a lever disconnected from said plunger operable at will for moving the plunger in an opposite direction, said plunger being provided intermediate its ends with gear teeth, a toothed segment, a spring acting on said segment to retain at least one tooth in mesh with the gear teeth of the plunger, and a pointer carried by the gear segment.

6. In a machine for assorting tiles according to their sizes, the combination of a bed having a tile-engaging surface, a tile-engaging member thereon, said member having a straight edge positioned perpendicularly to the tile-engaging surface, a plunger one end of which is in opposing relation to the tile-engaging member, said plunger having gear teeth, a spring for normally moving the plunger in one direction, a lever separate from the spring and disconnected from said plunger for moving the latter in an opposite direction, a gear segment meshing with the gear teeth of the segment, and a pointer carried by the gear segment, said plunger being rotatable, by hand, for the purpose of changing the line of contact of its teeth with the teeth of the gear segment.

7. In a machine for assorting tiles according to their sizes, the combination of a bed having a tile-engaging surface, a tile-engaging member thereon, a sliding plunger one end of which is in opposing relation to said tile-engaging member, said plunger being provided with circular gear teeth, a spring for normally moving the plunger in a direction toward, and to a predetermined position

relative to, said tile-engaging member, a hand lever free from direct connection with the plunger and operable to impart movement to said plunger in an opposite direction, a gear segment the teeth of which mesh with the teeth of said plunger, a spring acting on the gear segment, and a pointer carried by the segment, said plunger being rotatable at will relative to the gear segment for 10 changing the line of contact of the teeth on

said plunger with the teeth of the gear segment.

In testimony whereof I have signed my name to this specification in the presence of two subscribing witnesses.

GEORGE A. STANBERY.
